HIGH-PRESSURE RECIPROCATING COMPRESSOR

Application filed November 25, 1927, Serial No. 235,534, and in Switzerland November 30, 1926.

This invention relates to high pressure piston or reciprocating compressors. In all piston or reciprocating machines having a crank drive the guides or stuffing boxes are exposed to primary deformations owing to the weight of the piston rods, whilst the frictional forces produce secondary deformations. While it is difficult to eliminate the leaks caused by these primary deformations in reciprocating machines working with high pressures, such as high pressure reciprocating compressors, it is practically impossible to maintain a tight joint in the packings of compressors working under extremely high pressures owing to the action of the secondary deformations on the packing devices.

The object of this invention is to relieve the guide or the stuffing box of such super high pressure compressors and to eliminate the secondary deformations which normally occur with a crank device and cause leakage.

According to this invention the power is transmitted from the driving apparatus to the compressor pistons through an oscillating column of liquid which may, for example, be acted upon by an intermediate piston forming part of the driving apparatus. This column may be interposed directly between the piston which is driven by the prime mover and hereafter called the driving piston and the compressor piston or between the driving piston and an intermediate piston mechanically connected to the compressor piston, the liquid column being, if desired, sub-divided into several columns each controlling a separate compressor stage.

Some of the stages, for instance, those which are vertically disposed, may be actuated by the liquid columns and the remaining stages—for example, those which are disposed horizontally may be actuated mechanically. The hydraulically acting stages may be mounted upon a part of the driving apparatus.

The invention may be carried into practice in various ways but three constructions according thereto are illustrated diagram-

matically by way of example in the accompanying drawings, in which

Figure 1 illustrates in cross-section a seven stage compressor in which all the stages are driven by means of oscillating 55 columns of liquid,

Figure 2 is a cross-sectional elevation of a three stage compressor partially mechanically operated, and

Figure 3 is a cross-sectional elevation of 60 another form of three stage compressor operated wholly by means of liquid columns.

In the construction illustrated in Figure 1 the power is transmitted from the main shaft 1 of the driving apparatus through a connecting rod 2, and crosshead 3 to a piston rod 4 on which are mounted driving pistons 5, 6 and 7 acting respectively on columns of liquid adapted to oscillate within cylinders 8, 9 and 10 separated by members 38 and 39. Each of the columns in the cylinders 8 and 9 is sub-divided into two columns 11, 12 and 13, 14 respectively acting on intermediate pistons 31, 32 and 33, 34. The column 15 in the cylinder 10 is subdivided into three columns *a*, *b* and *c* which act respectively on intermediate pistons 35, 36 and 37.

The working pistons 17, 18, 19, 20, 21, 22 and 23 of the compressor are disposed within 80 cylinders 24, 25, 26, 27, 28, 29 and 30 and are mechanically connected to the intermediate pistons 31, 32, 33, 34, 35, 36 and 37 respectively so as to be actuated by the columns of liquid 11, 12, 13, 14, *a*, *b* and *c*.

The driving piston rod 4 is provided with stuffing boxes 40, 41, 42, 43 and 44 where it enters and leaves the cylinders 8, 9 and 10, these stuffing boxes being only subjected, however, to a liquid at relatively low pressure since the area of the intermediate pistons is made considerably larger than that of the working pistons of the compressor. The fluid to be compressed, for example a gas, enters the cylinders of the compressor through inlet ports 45, 46, 47, 48, 49, 50 and 51 and leaves by way of discharge ports 52, 53, 54, 55, 56, 57 and 58, the inlet pipes, valves, receivers and other details being omitted for the sake of clearness. The various

pressure stages are indicated by Roman numerals.

It will be seen that as the driving pistons 5, 6 and 7 reciprocate within their cylinders the columns of liquid will oscillate and cause the compressor pistons to reciprocate also. In the construction illustrated in Figure 2 the first stage of the compressor is actuated mechanically its piston 61 being mounted on the same rod 4 as the piston 60 which acts on the column of liquid. The main column of liquid is disposed within a cylinder 64 separated from the first stage cylinder 62 by means of a member 63, and is sub-divided into two columns 81 and 82 respectively acting upon intermediate pistons 83 and 84. On the cylinder 64 are mounted the cylinders 65 and 66 which, together with their pistons 67 and 68 constitute the second and third stage of the compressor. The fluid to be compressed is supplied to the first stage through the inlet ports 69 and 70 and is discharged therefrom through the ports 71 and 72. It enters the second and third stages through ports 73 and 75 respectively and is discharged through ports 74 and 76.

The cylinders 65 and 66 are supported on members 77 and 78 carried by the cylinder 64 and the pistons 67 and 68 are respectively connected at their lower ends to the intermediate pistons 83 and 84, stuffing boxes 79 and 80 being provided to prevent leakage round the stems of the pistons 67 and 68. As in the construction of Figure 1 the oscillating columns of liquid 81 and 82 act on the pistons 83 and 84 and thus cause the compressor pistons 67 and 68 to reciprocate.

In order to replace the liquid lost through leakage a separate pump may be provided in which case passages 87 and 88 are provided in the cylinders of the pistons 83 and 84 through which any excess of liquid supplied by the pump can escape into the chambers 89 and 90 as soon as the pistons 83 and 84 reach their uppermost position. In this manner are avoided shocks caused by the pistons 67 and 68 coming into contact with the cylinder covers 85 and 86.

In the further modification illustrated in Figure 3 the driving piston which acts on the column of liquid is in the form of a differential piston 92, 93 adapted to reciprocate within a cylinder 91 and the column of liquid is sub-divided into three columns 96, 97 and 98 corresponding to the three stages II, III and I of the compressors. These three stages are all mounted on the cylinder 91 and the admission and discharge of the fluid to be compressed is carried out in the same manner as in the constructions described above, the direction of flow being indicated by arrows.

It will be understood that the stroke of the intermediate pistons 31 to 37 in Figure 1 may be varied by altering the ratio between

the areas of these pistons and the areas of the driving pistons 5, 6 and 7. Moreover it will be observed from the drawings that there is ratio between the diameter of the driving piston and the diameter of the compressor pistons, depending on the particular stage in which they work. That is, with reference to Fig. 2 it will be noted that the diameter of the piston 83, when compared with that of the piston 67, is such that its area is perhaps nine times the area of the piston 67. Likewise the area of the piston 84 is perhaps thirty times the area of the piston 68. If, therefore, for example, the compressor is to condense to a pressure of 180 atmospheres in the second stage and to a pressure of 600 atmospheres in the third stage, the pressure in the liquid column can be adjusted to approximately 20 atmospheres in view of the foregoing ratio. It is accordingly possible in applicant's arrangement to provide a compressor wherein the condensation pressure may be increased many times while the liquid column is maintained at a relatively low pressure. While the foregoing ratio of piston area has been pointed out with particular reference to Fig. 2 it is to be observed that a similar ratio is apparent from the drawings as shown in stages III-VII of Fig. 1 and stages II and III of Figs. 2 and 3.

The arrangement according to the invention may be such that a single stage only is actuated by the movement of the liquid column. The invention however, may be applied to crank-driven compressors or pumps of any known construction whether of the tandem, twin or stage type.

The arrangement according to the invention of the cylinders, more particularly of the high pressure stages of pumps and compressors, allows them to be readily centered with considerable accuracy, all stresses on the moving parts acting only centrally. In this way secondary deformation is avoided and the fluid tightness of such stuffing boxes as are employed is ensured. In addition the arrangement described above makes it possible to accommodate a compressor having a given number of stages within a smaller space than would be the case with the compressors hitherto known.

It will be appreciated that while the invention has been described as particularly applied to compressors, it may equally well be applied to reciprocating pumps.

Any suitable liquid may be employed to transmit power from the driving piston to the compressor piston but oil is preferably used since it serves to lubricate those parts of the apparatus with which it comes into contact.

In particular, the present invention not only makes possible the prevention of deformations of a secondary character between

the piston rods and their packing, which are injurious to compressors working with 1000 and more atmospheres, but it also makes possible a very large increase in the pressure which may be used in the compression cylinders. In so doing, applicant's invention obviates the necessity and disadvantages of complex packing members for the liquid columns and a complicated construction of the cylinders, and makes possible the maintenance of 10 the liquid column at a pressure amounting to only a fractional part of the condensation pressure.

I claim:

1. In a high pressure reciprocating compressor, the combination of a driving cylinder having a piston mounted for movement therein, a plurality of vertically disposed compressor cylinders, a compressor piston mounted for movement within each of the compressor cylinders, and an oscillatable column of substantially incompressible liquid for transmitting power from said driving cylinder to the compressor pistons, said column being branched into several component columns each actuating a separate compressor piston.

2. In a high pressure reciprocating compressor, the combination of a driving cylinder having a piston mounted for movement therein, a plurality of vertically disposed compressor cylinders, a compressor piston mounted for movement within each of the compressor cylinders, and an oscillatable column of incompressible liquid for transmitting power from said driving cylinder to each of the compressor pistons.

3. In a high pressure reciprocating compressor, the combination of a driving cylinder having a piston mounted for movement therein, horizontally and vertically disposed compressor cylinders, a compressor piston mounted for movement within each of said compressor cylinders, means for transmitting power from said driving cylinder to said horizontally disposed compressor piston, and an oscillatable column of incompressible liquid for transmitting power from said driving cylinder to said vertically disposed compressor piston.

4. In a high pressure reciprocating compressor, the combination of a driving apparatus, a horizontal driving cylinder having a piston mounted for movement therein, a plurality of vertically disposed compressor cylinders, a compressor piston mounted for movement within each of the compressor cylinders, means for transmitting power from said driving apparatus to the piston within the horizontally disposed cylinder, and an oscillatable column of incompressible liquid for transmitting power from said driving cylinder to said compressor pistons.

5. In a high pressure reciprocating compressor, the combination of a driving cylin-

der having a piston mounted for movement therein, horizontally and vertically disposed compressor cylinders, a compressor piston mounted for movement within each of said compressor cylinders, an oscillatable column of liquid for transmitting power from said driving cylinder to said vertically disposed compressor piston, and mechanical means for transmitting power from said driving cylinder to said horizontally disposed compressor piston.

6. In a high pressure reciprocating compressor, the combination of a driving cylinder having a piston mounted for movement therein, a plurality of separate compressor cylinders vertically mounted on said driving cylinder, a compressor piston movable within each of said compressor cylinders, and an oscillatable column of liquid for transmitting power from said driving cylinder to said compressor pistons.

7. In a high pressure reciprocating compressor, the combination of a driving cylinder having a piston mounted for movement therein, horizontally and vertically disposed compressor cylinders, a compressor piston movable within each of said compressor cylinders, an oscillatable column of liquid for transmitting power from said driving cylinder to said vertically disposed compressor cylinder, the piston of said driving cylinder and the piston of said horizontally disposed compressor cylinder being mounted on the same piston rod.

8. In a high pressure reciprocating compressor, the combination of a driving apparatus, a driving cylinder having a piston mounted for movement therein, horizontally and vertically disposed compressor cylinders, a compressor piston movably mounted in each of said compressor cylinders, an oscillatable column of liquid for transmitting power from said driving cylinder to said vertically disposed compressor piston, and mechanical means for transmitting power from said driving cylinder to said horizontally disposed compressor piston, said driving cylinder being disposed between said driving apparatus and said horizontally disposed compressor cylinder.

9. In a high pressure reciprocating compressor, the combination of a driving piston movable within a cylinder, a compressor piston movable within a compressor cylinder, an intermediate piston movable within an intermediate cylinder, and an oscillatable column of substantially incompressible liquid disposed between said driving piston and said intermediate piston for transmitting power from said driving piston to said compressor piston, said intermediate piston having such a diameter relatively to the compressor piston that a high degree of compression is obtained in the compressor cylinder.

der without a corresponding increase in the pressure of said liquid column.

10. In a high pressure reciprocating compressor, the combination of a driving apparatus, a horizontally disposed primary piston movable within a cylinder, a vertically disposed compressor piston movable within a compressor cylinder, an intermediate piston movably mounted within a cylinder and connected to said compressor piston, and an oscillatable column of substantially incompressible liquid disposed between said primary piston and said intermediate piston to transmit power from the primary piston to the compressor piston, said intermediate piston having such a diameter relatively to said compressor piston that a high degree of compression is obtained in the compressor cylinder without a corresponding increase in the pressure of said liquid column.
15. In a high pressure reciprocating compressor, the combination of a horizontally disposed primary piston movable within a cylinder, a vertically disposed compressor piston mounted within a compressor cylinder, an intermediate piston movable within a cylinder and connected to said compressor piston, and an oscillatable column of substantially incompressible liquid disposed between said primary piston and said intermediate piston to transmit power to said compressor piston, said intermediate piston having such a diameter relatively to said compressor piston that a high degree of pressure is obtained in the compressor cylinder without a corresponding increase in the pressure of said liquid column.
20. In a high pressure reciprocating compressor, the combination of a horizontally disposed primary piston movable within a cylinder, a vertically disposed compressor piston mounted within a compressor cylinder, an intermediate piston movable within a cylinder and connected to said compressor piston, and an oscillatable column of substantially incompressible liquid disposed between said primary piston and said intermediate piston to transmit power to said compressor piston, said intermediate piston having such a diameter relatively to said compressor piston that a high degree of pressure is obtained in the compressor cylinder without a corresponding increase in the pressure of said liquid column.

In testimony whereof I have affixed my signature.
